UNITED STATES PATENT OFFICE.

LADISLAV KAPLAN, OF CLINTON, CONNECTICUT.

CALIPERS.

1,194,182.

Specification of Letters Patent.

Patented Aug. 8, 1916.

Application filed January 4, 1916. Serial No. 70,146.

To all whom it may concern:

Be it known that I, LADISLAV KAPLAN, a citizen of the United States, and a resident of Clinton, in the county of Middlesex and State of Connecticut, have invented a new and Improved Calipers, of which the following is a full, clear, and exact description.

Among the principal objects which the present invention has in view are: to provide a scale for recording the space separating the ends of the caliper arms; to provide simple and efficient means for magnifying the reading of the scale; to provide means for facilitating the operation of the calipers; and to provide means for setting the calipers for an established measurement.

Drawings.—Figure 1 is a side view of a calipers constructed and arranged in accordance with the present invention; Fig. 2 is a section on an enlarged scale, the section being taken as on the line 2—2 in Fig. 1; Fig. 3 is a detail view partly in section, the section being taken as on the line 3—3 in Fig. 2; and Fig. 4 is a section on an enlarged scale taken as on the line 4—4 in Fig. 1.

Description.—The calipers shown in the drawings is specially adapted for employment in the manufacture of violins and is provided with a handle 9. The handle 9 may be formed of metal or wood as desired and is rigidly connected with a haft 10 of the arm 11. The arm 11 is curved at the outer end to form the horn 12. The arm 11 and horn 12 may or may not correspond in shape to the arm 13. In instances where the use suggests the change, the arm 13 is shaped to a greater or lesser curve than is shown for the horn 14 of the said arm. In many instances the horn 14 is joined to the body of the arm 13 by a large bellied section, the purpose being to reach over and encompass the material being handled without interference therewith.

The arm 13 is removably mounted on a U-shaped section 15, one arm of which has a hole to receive a locating pin 16 and an elongated slot 17, through which a stud screw 18 may be extended. The arm 13 and various substitutes therefor used in connection with the calipers are each provided with a pin 16 and screw 18. The various screws are engaged in service by a milled or other form of screw nut 19, which when

tightened operates to clamp rigidly in service position the arm 13.

The function of the slot 17 is to permit the slight adjustment of the arm 13 and substitutes therefor at times found necessary. At all times, this adjustment is made so that the ends of the horns 12 and 14 of the two arms 11 and 13 or the substitutes therefor are in contact and the pointer 20 is registered with the zero mark on the calibrated scale blade 21.

The section 15 is pivotally mounted by means of the screw 22 on the arm 11. The section 15 is normally rotated on the screw 22 to hold the ends of the horns 12 and 14 in contact. This office is performed by a coil spring 23, which is housed in a recess formed in a bracket 24 rigidly mounted on the arm 11. The free end of the spring 23 is fixedly attached to a pivot pin 25. The pin 25 is rigidly connected with a gear wheel 26. The teeth of the wheel 26 mesh with the teeth of a gear segment 27 at one end of the section 15.

The section 15, as stated, is rocked on the screw 22 and for this purpose the said section is provided with a trigger 28 conveniently located with reference to the handle 9. When the said trigger is drawn upon, the section 15 is rocked so that the arm 13 is moved from the arm 11 and the segment 27 moves to rotate the wheel 26, so that the end of the pointer 20 moves over the calibrations on the blade 21. To this end and as best shown in Fig. 2 of the drawings, the pointer 20 is fixedly connected by the arm 29 with the wheel 26.

The difference in the length of the diameter of the wheel 26 and the distance from the center of the said wheel to the end of the pointer 20 corresponds with the ratio of movement of the wheel 26 and the section 15 connected therewith to the free end of the pointer 20. The magnified reading thus produced corresponds with the calibrations on the blade 21.

It is some times found convenient to set the calipers so that the horns 12 and 14 are separated at an established distance. This is accomplished by providing a pin 30 on one of the arms of the section 15. The pin 30 extends into the path of a small cam 31. The cam 31 is fixedly attached to a milled wheel 32. The wheel 32, as is best seen in Fig. 2 of the drawings, is normally held by

- a spring drag 33 disposed between the said wheel and the face of the arm 11. Preferably the wheel 32 is disposed convenient to the thumb of the person using the calipers.
- 5 When so disposed, it will be seen that the wheel 32 may be turned until the user by watching the movement of the pointer 20 on the blade 21 may ascertain the space between the horns 12 and 14. Thereafter the pointer 10 will always return to the position set and held by the cam 31 by reason of the fact that the pin 30 swings back to and engages the surface of the said cam.

To ease the operation of the calipers, the 15 screw 22 has a cap 34, wherein a circular groove is formed as a race for balls 35. A similar set of balls is disposed in a groove formed in the section 15 concentric to the screw 22. The two sets of balls 35 form 20 a suitable ball bearing, which provides a smooth operating joint for the said section 15 and the arm 11.

Claims:

1. Calipers comprising a stationary arm; 25 a movable arm; means pivotally connecting said arms intermediate the ends of said movable arm; a calibrated blade fixedly mounted on said stationary arm and extending outwardly therefrom; a pointer pivotally mounted on said stationary arm with the free end of said pointer moving in juxtaposed relation with said blade; means for rotating said pointer in correspondence with the movement of said movable arm, said 30 means embodying a wheel supporting said pointer; means on the adjacent end of said movable arm rotatively engaging said wheel; a handle fixedly mounted on said stationary arm; and a trigger mounted on said 35 movable arm in juxtaposed relation to said handle for rotating said movable arm on its pivotal mounting.

2. Calipers comprising a stationary arm; 45 a movable arm; means pivotally connecting said arms intermediate the ends of said movable arm; a calibrated blade fixedly mounted on said stationary arm and extending outwardly therefrom; a pointer pivotally mounted on said stationary arm with the 50 free end of said pointer moving in juxtaposed relation with said blade; means for rotating said pointer in correspondence with the movement of said movable arm, said means embodying a wheel supporting said pointer; means on the adjacent end of said movable arm rotatively engaging said wheel; a handle fixedly mounted on said stationary arm; a trigger mounted on said 55 movable arm in juxtaposed relation to said handle for rotating said movable arm on its pivotal mounting; and means mounted 60 on one of said arms for engaging the other

of said arms to regulate the spacing of the free ends thereof.

3. Calipers comprising a stationary arm; 65 a movable arm; means pivotally connecting said arms intermediate the ends of said movable arm; a calibrated blade fixedly mounted on said stationary arm and extending outwardly therefrom; a pointer pivotally mounted on said stationary arm with the free end of said pointer moving in juxtaposed relation with said blade; means for rotating said pointer in correspondence with the movement of said movable arm, said 70 means embodying a wheel supporting said pointer; means on the adjacent end of said movable arm rotatively engaging said wheel; a handle fixedly mounted on said stationary arm; a trigger mounted on said 75 movable arm in juxtaposed relation to said handle for rotating said movable arm on its pivotal mounting; and means for engaging said arms to regulate the spacing of the free ends thereof, said means embodying a cam 80 rotatively mounted on said stationary arm, and a pin on said movable arm, said pin extending into the path of said cam for engagement therewith.

4. Calipers comprising a stationary arm; 90 a movable arm; means pivotally connecting said arms intermediate the ends of said movable arm; a calibrated blade fixedly mounted on said stationary arm and extending outwardly therefrom; a pointer pivotally 95 mounted on said stationary arm with the free end of said pointer moving in juxtaposed relation with said blade; means for rotating said pointer in correspondence with the movement of said movable arm, said 100 means embodying a wheel supporting said pointer; means on the adjacent end of said movable arm rotatively engaging said wheel; a handle fixedly mounted on said stationary arm; a trigger mounted on said 105 movable arm in juxtaposed relation to said handle for rotating said movable arm on its pivotal mounting; means for engaging said arms to regulate the spacing of the free ends thereof, said means embodying a cam 110 rotatively mounted on said stationary arm, and a pin on said movable arm, said pin extending into the path of said cam for engagement therewith; and a wheel rigidly connected with said cam in juxtaposed relation to the handle of said calipers for moving said cam.

In testimony whereof I have signed my name to this specification in the presence of two subscribing witnesses.
